SKI AND SKI POLE HOLDER

James W. Donaldson, 8905 W. Bayaud Ave.,
Lakewood, Colo. 80226

Filed Jan. 8, 1975, Ser. No. 539,464

Term of patent 14 years

Int. Cl. D6—04

U.S. Cl. D6—125

Fig. 1

Fig. 4

Fig. 2

Fig. 3

FIG. 1 is an isometric view of my novel and ornamental design for a ski and ski pole holder.

FIG. 2 is a front elevational view thereof.

FIG. 3 is a side elevational view taken from the right of FIG. 1.

FIG. 4 is a top plan view thereof.

The back of the ski and ski pole holder is plain and unadorned.

I claim:

The ornamental design for a ski and ski pole holder, as shown and described.
